UNITED STATES PATENT OFFICE.

WILLIAM ISAAC SIMPSON, OF VANCOUVER, BRITISH COLUMBIA, CANADA, ASSIGNOR
TO OLIVER LEWIS WARNER, OF VANCOUVER, BRITISH COLUMBIA, CANADA.

BLOCK-SIDE GUARD FOR UPRIGHT-SHINGLE-MACHINE SAWS.

1,302,445.

Specification of Letters Patent. Patented Apr. 29, 1919.

Application filed January 20, 1919. Serial No. 272,110.

To all whom it may concern:

Be it known that I, WILLIAM ISAAC SIMPSON, a subject of the King of Great Britain, and a resident of the city of Vancouver, in 5 the Province of British Columbia, Canada, have invented certain new and useful Improvements in Block-Side Guards for Upright-Shingle-Machine Saws, of which the following is a specification.

10 My invention relates to improvements in guards for saws, with particular reference to the saws of upright shingle machines, and the object of my invention is to devise a simple, cheap and effective guard adapted 15 to be placed on the block side of such saws the use of which eliminates the danger to the operator which exists where the saw is unguarded, such as the possible danger of having the fingers cut off or the hand otherwise injured.

I attain this object by the construction illustrated in the accompanying drawings in which—

20 Figure 1 is a perspective view of a portion 25 of the shingle machine and saw showing the application of my guard thereto.

Fig. 2 is a perspective view looking on the side opposite to that shown in Fig. 1.

Fig. 3 is a detail view of the guard, in 30 perspective.

Similar figures of reference indicate similar parts throughout the several views.

1 indicates a portion of an upright shingle machine and 2 the carriage between the upper and lower jaws 3 and 4 of which the shingle bolt is held to be cut by the saw 5. Secured to the back of the carriage as shown in Fig. 2 is a bracket 6 one arm of which extends parallel with the side of the saw 40 and adjustably mounted on this bracket 6 is another bracket 7 the horizontal arm 8

of which extends toward the saw at right angles to the bracket 6, a locking screw 9 being provided for locking the bracket in any adjusted position. The bracket 7 is 45 provided with an upstanding arm 10 to which is secured a guard formed out of a flat plate 11, of wood or any other suitable material, the outer edge of which is curved as shown and extends beyond the saw teeth 50 about three inches, and the arrangement and length of the brackets 6 and 7 is such that when the device is assembled the guard 11 lies close against the saw on the block side so that it will be seen that there is therefore 55 no space for the fingers of the operator to get into, so that should the fingers slip when operating the machine in proximity to the saw no harm can result, as they strike the forward edge of the guard, whereas without 60 the guard a slip of the fingers would probably result in their being cut off by the saw.

It will thus be seen that I have devised a simple and inexpensive saw guard the use of which provides safety to the operator 65 of upright shingle bolt machines.

What I claim as my invention is:

The combination with an upright shingle machine frame and saw, of an L-shaped bracket secured to the machine carriage having 70 its long arm extending parallel to the saw on the block side of the same, a second L-shaped bracket mounted on the said long arm for longitudinal adjustment thereon, a guard plate secured to the free end of the 75 second mentioned bracket having its forward edge extending in advance of the saw teeth, and means for securing said bracket in its adjusted position.

Dated at Vancouver, B. C., this 10th day 80 of January, 1919.

WILLIAM ISAAC SIMPSON.
